UNITED STATES PATENT OFFICE.

GEORGE L. WALKER, OF NEW YORK, N. Y., ASSIGNOR TO AIR REDUCTION COMPANY,
INC., A CORPORATION OF NEW YORK.

BLOWPIPE.

1,387,435.

Specification of Letters Patent.

Patented Aug. 9, 1921.

Original application filed May 1, 1919, Serial No. 294,004. Divided and this application filed November 20, 1920. Serial No. 425,334.

To all whom it may concern:

Be it known that I, GEORGE L. WALKER, a citizen of the United States, residing at New York, in the county of New York, State of New York, have invented certain new and useful Improvements in Blowpipes; and I do hereby declare the following to be a full, clear, and exact description of the invention, such as will enable others skilled in the art 10 to which it appertains to make and use the same.

This invention relates to blow pipes burning mixtures of combustible and oxidizing gases such as acetylene and oxygen and employed in heating, welding and cutting operations.

More particularly the invention involves an improvement in the blowpipes described in Letters Patent to George H. Zouck, No. 20 1310100 and No. 1310101, although the principles herein described may be employed in blowpipes differing in details of construction from those mentioned. The invention is in fact general application to blowpipes 25 having grooves in one of two coöperating surfaces, whereby one of the gases is conveyed to and mixed with the other to provide a combustible mixture which is discharged and burned to produce high temperature 30 flames.

The object of the invention is to improve the operation of blowpipes by insuring the proper mixture of the gaseous constituents and particularly to prevent "flash-back" or 35 backward propagation of the flame in the discharge passage of the blowpipe tip.

Further objects and advantages of the invention will be apparent as it is better understood, by reference to the following specification and accompanying drawing illustrating a preferred embodiment of the invention, in which:

Figure 1 is a longitudinal section through a blowpipe head and a portion of a tip;

Fig. 2 is a section in the line 2—2 of Fig. 1; and

Fig. 3 is a rear end elevation of the tip illustrated in Fig. 1.

It has been discovered as explained in the 50 Letters Patent to George L. Walker, No. 1310099 that the best results are obtained in the operation of blowpipes, when the pressure of the two gases are substantially equal or the pressure of the acetylene slightly ex-

ceeds that of the oxygen. In the operation 55 of blowpipes as usually constructed, any obstruction of the discharge passage results in an enrichment of the mixture in oxygen and corresponding increase in the rate of flame propagation therein. Usually a "flash-back" 60 results from this abnormal condition. In the operation of blowpipes as herein contemplated, this objectionable result is avoided. The pressures of the entering gases being substantially equal, any obstruction in the 65 discharge passage results in a decreased flow of both gases, while the mixture remains normal, or, if the pressure of the acetylene exceeds slightly that of the oxygen, the mixture is enriched in acetylene with corre- 70 sponding decrease in the rate of flame propagation in the mixture.

I have discovered that the operation of blowpipes in the manner described is materially improved when the combustible gas is 75 conveyed through passages of uniformly diminishing cross-sectional area and is mixed with the oxidizing gas immediately upon delivery from such passages. By conveying the combustible gas in this manner, the 80 maintenance of the desired velocity is assured, no opportunity being afforded for the gas to expand until it flows into the discharge passage of the tip. As a result of the operation as described, I find that the 85 character of the mixture is improved, and that regulation of the flame and the prevention or rearward propagation thereof are readily accomplished. The operation of the blowpipe, particularly by relatively unskilled operators is made comparatively simple.

Referring to the drawing in which the head and a portion of the tip are illustrated on an enlarged scale, to more clearly distinguish the invention, 5 indicates the head having passages 6 and 7 for oxidizing and combustible gases which are delivered thereto through pipes 8 and 9 from a suitable source. The passage 6 terminates at the 100 apex of a conical seat 10 in which an annular groove 11 is formed. Ducts 12 connect the channel with the passage 7.

A tip 13 having a discharge passage 14 is held in assembled relation with the head 105 5 by a nut 14'. The tip 13 is provided at its inner end with a conical recess, the surface of which conforms to the seat and forms

- therewith a gas tight joint surrounding the channel 11, and effectually preventing escape of gases from the head. One or more grooves 15 are milled, pressed or otherwise formed in the recessed surface and serve to convey the combustible gas from the channel 11 to the mouth of the discharge passage 14, where it mixes with the oxidizing gas from the passage 6.
- 10 It will be noted that the grooves 15 are comparatively shallow and of substantially uniform depth throughout. The width however of the grooves is uniformly diminished from the channel 11 to the discharge passage 14. The grooves form therefore when the tip is assembled with the head, a passage of uniformly diminishing cross sectional area as hereinbefore explained. The combustible gas issues therefore from these passages and is delivered to the oxidizing gas, at maximum velocity with resulting improvement of the mixture and other advantages.
- 15 It is to be understood that in the accompanying drawing I have illustrated a preferred mode of applying the invention, and that changes may be made therein by varying both the width and depth of the grooves
- to provide passage of uniformly diminishing cross-sectional area for the gas. The 30 depth and width of the grooves may be varied and are in fact carefully proportioned to provide proper mixtures in tips intended to produce flames of given dimensions. The invention is applicable, moreover, in blowpipes in which the combustible gas is conveyed to the oxidizing gas through grooves arranged otherwise than in the particular manner described, the peculiar results accomplished being attributable to the 35 uniformly diminishing cross sectional area of the passages.
- I claim:—
- In a blowpipe, the combination with a head having oxidizing and combustible gas 40 passages, of a tip adapted to be assembled therewith and provided with a discharge passage, said head having a projecting conical seat and said tip having a corresponding recessed surface provided with a groove of 45 substantially uniform depth and diminishing width to provide a passage of diminishing cross sectional area arranged to deliver combustible gas to said discharge passage.
- In testimony whereof I affix my signature. 50
GEORGE L. WALKER.
